(57) **CLAIM**

The ornamental design for a bodily fluid drainage bag cover, as shown and described.

DESCRIPTION

FIG. 1 is a front perspective view of a bodily fluid drainage bag cover in a partially raised state, showing my new design; FIG. 2 is a front perspective view of the bodily fluid drainage bag cover of FIG. 1 in a lowered state;

FIG. 3 is a front elevation view thereof;

FIG. 4 is a right side elevation view thereof, with the left side elevation view being a mirror image of FIG. 4;

FIG. 5 is a top elevation view thereof; and,

FIG. 6 is a bottom elevation view thereof.

The broken lines are directed to environment and are for illustrative purposes only; the broken lines form no part of the claimed design.
